UNITED STATES PATENT OFFICE.

WILLIAM ENGLAND, OF CALLAO, PERU.

TELEGRAM-BLANK.

1,028,695.

Specification of Letters Patent. Patented June 4, 1912.

Application filed February 18, 1911. Serial No. 609,427.

To all whom it may concern:

Be it known that I, WILLIAM ENGLAND, a subject of the King of Great Britain, and a resident of Callao, Peru, have invented a 5 new and Improved Telegram-Blank, of which the following is a full, clear, and exact description.

Among the principal objects which the present invention has in view are: to provide 10 a sheet constructed and arranged to form coincidently with the marking of an original written copy a transfer duplicate thereof; and to form a semi-transparent duplicate blank having a transfer coating formed on a section thereof to vary the color of the same on the side opposite that upon which the transfer material is placed, and by omission to form thereon ruled lines to show on the face of the said section.

20 One embodiment of the present invention is disclosed in the structure illustrated in the accompanying drawings, in which like characters of reference denote corresponding parts in all the views, and in which—

25 Figure 1 is a view of a telegram blank constructed and arranged in accordance with the present invention, the blank being illustrated in its spread position prior to being folded in its normal position; Fig. 2 30 is a view of a fragment of telegram blank constructed and arranged in accordance with the present invention, showing two sections of the blank, the under or transfer side of the section to receive the original 35 message and the face of the section to which the message is transferred; and Fig. 3 is a view of the blank in its normal position, showing in connection therewith the manner 40 of imparting a message to the original section, and showing a part of the transferred message, the corner of the receiving section of the blank being turned back to show the copy section and the message transferred thereto.

45 As shown in the accompanying drawings, the entire blank is constructed from semi-transparent paper and is divided by a perforated or score line 8 into a receiving section 9 and a copying section 10. Both sections 50 are printed upon at the same impression and on the same side of the blank. The ink employed is specially prepared, being adapted to transfer without smudging, and to be used upon the ordinary platen printing press.

The printed impressions are applied to

the paper preferably by means of a block which is engraved to imprint the receiving section 9 with a solid surface 11, which subsequently forms the material by means of 60 which the transfer copy is imprinted to the copy section 10. As best seen in Fig. 2 of the drawings, the surface 11 is provided with a number of ruled lines and alphabetical letters indicative in character and 65 for the guidance of the user of the blank. The lines thus prepared are formed by omission of the surface 11, this being performed under usual conditions by graving the lines and letters in the block or plate from which 70 the blanks are printed. The wording, lines and letters imprinted upon the copy section 10 are, as shown in Fig. 2 of the drawings, what might be termed regularly placed. By arranging for the simultaneous impression 75 the transfer surface, therein providing for the necessary ruled lines for the handling of the blank and the lines, words and letters imprinted upon the copy section, the cost of the blanks is minimized. When 80 printed in the manner described, and after the ink has dried, the blank is folded, as shown in Fig. 3 of the drawings, upon the perforated or score line 8. In this form the blank is distributed for use.

85 In the employment of the blank as shown best in Fig. 3 of the drawings, the proper station from which the message is sent, directions, date and other data are written upon the receiving section 9 and upon the 90 surface thereof uppermost when in position for use, employing for guidance, in placing the writing, the light lines formed by the omission of the surface 11 on the under side of the receiving section 9. The 95 transfer from the receiving section 9 to the copy section 10 is in the manner usual to transfers of this character.

In employing the blank, the sections 9 and 10 are severed on the line 8, and the 100 copy section 10 is retained by the customer, while the section 11 is delivered to the company.

Having thus described my invention, what I claim as new and desire to secure by Letters Patent is:—

A semi-transparent telegram blank folded to form two sections, one of said sections having imprinted lines and words, and the other of said sections having imprinted a 110 body coating of transfer material, said coating being omitted to form lines and words

in intaglio to govern the writing on the folded blank, said imprint on both sections being on the same side of the outspread blank, and said lines and words of the two sections registering when said sections are folded.

In testimony whereof I have signed my

name to this specification in the presence of two subscribing witnesses.

WILLIAM ENGLAND.
